UNITED STATES PATENT OFFICE

166,373

EXPANSIBLE BRACELET

William C. Boots, Rumford, R. I.

Application December 17, 1951, Serial No. 17,757

Term of patent 14 years

(Cl. D45—4)

To all whom it may concern:

Be it known that I, William C. Boots, a citizen of the United States, residing at Rumford, in the county of Providence and State of Rhode Island, have invented a new, original, and ornamental Design for an Expansible Bracelet, of which the following is a specification, reference being had to the accompanying drawing, forming a part thereof, in which:

Fig. 1 is a plan view of an expansible bracelet, showing my new design;

Fig. 2 is a fragmentary plan view showing the bracelet in expanded condition; and

Fig. 3 is a bottom plan view corresponding to Fig. 1.

I claim:

The ornamental design for an expansible bracelet, substantially as shown.

WILLIAM C. BOOTS.
